Brooklyn, N. Y., a corporation of New York

Application April 27, 1932, Serial No. 607,692

16 Claims. (Cl. 107—60)

The present invention relates to ovens and embodies, more specifically, an improved gas oven for bakeries wherein the heat of the oven chamber is derived from two independent sources, each 5 of which may be separately controlled, and the products of combustion of which are directed to suitable exhaust stacks in such fashion that the full effect of each heat source is obtained.

In gas ovens now available the heat which is 10 supplied to the oven is derived either from a single or a plurality of sources, such as a gas flame, the products of combustion of which are not definitely directed in any particular course through the oven to an exhaust stack. Consequently considerable difficulty has been experienced in providing a uniform temperature throughout the oven and in varying such temperatures between desired limits effectively. 15 Hence the factor of oven controllability, upon which uniformity of bake is dependent, has not heretofore been satisfactorily met.

In this connection, the present invention contemplates the provision of improved controllability by directing the products of combustion 20 from separate heat sources through heat paths, each of which has its own exhaust stack. At each heat source, the ventilation of the oven is controlled by admitting the correct amount of secondary air, whereby greater flexibility of heat regulation throughout the oven is afforded. With greater flexibility of heat regulation the volume 25 of the oven may be decreased.

Greater economy of operation is attained by the present invention by reason of the elimination 30 of forced draft as well as because of a greater workable hearth area and less oven volume for a given capacity. The secondary air control enables the amount of air supplied to be definitely controlled, thus eliminating the loss 35 of heat heretofore required to heat the excess air necessarily supplied.

Further improved characteristics will appear 40 hereinafter and the present invention has for an object the provision of an improved form of oven in which the possibility of explosion during operation is reduced to an absolute minimum.

A further object of the invention is to provide 45 a gas oven wherein an exhaust damper and main gas supply valve are effectively controlled to insure proper coordination therebetween to prevent explosions within the oven.

A further object of the invention is to provide 50 an improved control mechanism for gas ovens whereby the exhaust damper and main gas supply are interlocked in such fashion that the

main gas supply may be opened only when the exhaust damper is open.

A further object of the invention is to provide 5 a gas oven provided with a plurality of heat sources, the gases from each heat source being separately directed to exhaust ducts.

A further object of the invention is to provide 10 a gas oven having a plurality of independent heat sources, the gases from the respective heat sources being effectively directed into the oven chamber, or in operative relation thereto, to maintain a uniform desired heat therein.

A further object of the invention is to provide 15 a gas oven having top and bottom heat sources, each heat source being separately controlled and the flow of gas therefrom being separately directed into operative relation with respect to the oven chamber and to exhaust ducts.

A further object of the invention is to provide 20 a gas oven having a plurality of separate heat sources, the flow of gases from which are controlled independently, properly located top and bottom heat cooling dampers being provided to control the temperature of the oven effectively.

A further object of the invention is to provide 25 an improved heat supply mechanism for gas ovens wherein a secondary air supply is provided for a burner, the quantity of air supplied thereby being automatically regulated in accordance with the operation of the burner.

A further object of the invention is to provide 30 a gas oven wherein a plurality of heat sources are provided and means is provided to direct the hot gases from the sources into the oven in such fashion that the temperature within the oven 35 chamber is substantially uniform at all points therein and wherein means is provided for effectively regulating such temperature between desired limits, the oven structure being airtight and of a compact nature.

Further objects, not specifically enumerated 40 above, will be apparent as the invention is described in greater detail in connection with the accompanying drawings, wherein:

Figure 1 is a view in vertical section, taken in 45 a plane passing through the axis of an oven constructed in accordance with the present invention and showing the plurality of heat sources from which the oven heat is derived, as well as the ducts, dampers and controlling mechanism therefor.

Figure 2 is an enlarged view showing the control mechanism for the exhaust damper and main gas supply mechanism of the present invention.

Figure 3 is a segmental view in side elevation 50

showing the control mechanism of Figure 2, the view being taken from the left, as viewed in Figure 2.

Figure 4 is a segmental view in horizontal section, looking down upon a burner constituting one of the heat sources of the present invention, this view illustrating the control mechanism for the secondary air supply device.

Figure 5 is an enlarged segmental view, similar to Figure 1, showing the secondary air supplying structure in detail.

With reference to the accompanying drawings, the oven structure embodying the present invention will be seen to include a rotatable hearth 10 which is mounted upon a shaft 11, journaled at 12 in the oven foundation 13. A step bearing 14 is provided to carry the weight of the hearth while a bearing 14' is provided to journal the top of shaft 11. A suitable driving mechanism 15 affords a means for rotating the shaft 11 and hearth 10.

Arms 16 may be provided to brace the hearth and enable the same to be mounted and supported effectively upon the shaft 11, the hearth being formed with an apron baffle 17 centrally thereof to form a vertical duct 18 through which heat may flow from a supply duct 19 in the oven foundation. The apron baffle 17 may be mounted upon the shaft 11 by means of arms 20 and a lower heat trap 21 is provided between the oven foundation and apron baffle 17 to prevent heated gases from the supply duct 19 from passing into the chamber below the hearth 10. This lower heat trap may be formed of an annular stationary member which is U-shaped in cross section and mounted in the oven foundation 13, the lower extremity of the apron baffle 17 being received therein to afford an effective baffle and obstruction against fluid flow therethrough.

A burner 22 is provided at the entrance to the duct 19 and constitutes a heat source for supplying heat to the chamber above the hearth through the duct 19 and apron baffle 17. Secondary air ducts 23 are formed in the oven foundation, the flow of air being controlled in a manner described hereinafter.

Above the rotatable hearth 10, an oven crown 24 is provided, the heated gases from the duct 18 flowing upwardly against the crown 24 and being directed downwardly therefrom onto the hearth 10. Top heat flues 25 are formed in the oven crown and are preferably spaced at 90° therein, whereby heated gases from the chamber above the burner may be removed at four spaced points at the sides of the oven. In order that the full effect of the top heat source may be felt in all parts of the chamber above the hearth, the entrances 26 to the flues 25 are formed at substantially the level of the hearth. In this fashion, the heated gases will be directed downwardly against the hearth before flowing into the exhaust flues. The four or more exhaust flues 25 preferably lead to a vertical stack 27 into which the heated gases flow from the flues. An exhaust damper 28 may be mounted slidably in the stack to control the flow of gases therethrough, the damper 28 being operated in a manner described hereinafter.

Beneath the hearth 10 and the chamber between the hearth and crown 24 which constitutes the baking chamber, a bottom heat chamber 29 is provided. This chamber is sealed from the baking chamber by means of a cylindrical skirt 30 which is formed upon the hearth 10 and which is received within a cooperating cylindrical seal-

ing member 31. The bottom heating chamber 29 is provided with a burner recess 32 in which a plurality of burner units 33 are mounted, longitudinal baffles 33' being provided between adjacent burners to facilitate the regulation of secondary air thereto. These burner units are supplied with gas from a gas pipe 34 which is connected to a main gas pipe 35. Each burner unit 33 is provided with a valve and valve operating handle 36 to control the flow of gas from the pipe 34 to the respective burner unit, and the valve spindle has secured thereto a gear sector 37 which is adapted to engage teeth 38 formed in a plate 39 which is slidably mounted in brackets 40 beneath the respective burner units 33.

The oven foundation 13 is formed with a recess 41 beneath the burner units 33 and this recess receives the plates 39. Secondary air ducts 42 communicate between the burner recess 32 and the recess 41 and thus provide a source of secondary air for the respective units. Plate 39 is formed with a plurality of apertures 43, corresponding in number and position to the ducts 42, whereby the secondary air ducts are opened simultaneously with the opening of the respective valve units 36.

The heated gases from the burner unit 33 flow upwardly against the under surface of the rotatable hearth 10 and through the bottom heat chamber 29 to an outlet duct 44 which communicates with a bottom heat stack 45. The duct 44 is preferably placed adjacent the bottom of the chamber 29 to build up a depth of heating gas practically equivalent to the bottom heat chamber 29. In as much as the duct 44 is diametrically opposed to the burner units 33, the heated gases from the latter must necessarily flow entirely through the chamber 29 before being discharged, thus utilizing a maximum amount of heat therefrom.

In order that the temperature of the oven may be effectively and quickly controlled, top and bottom heat cooling dampers 47 and 48 are provided, respectively. These dampers may be of usual form and are actuated by rods 49 and 50, respectively, the rods being connected to bell crank levers 51 and 52, respectively. Bell crank 51 is actuated by an operating rod 53 having a handle 54 while a bell crank lever 52 is actuated by a rod 55 upon which a handle 56 is formed. When dampers 47 and 48 are opened, cooling air is admitted into the top and bottom chambers to effect the rapid cooling thereof. In as much as, during the normal operation of an oven, baking operations requiring widely varying temperatures may be met with, the cooling damper construction is of considerable importance in as much as such baking operations may take place successively without any substantial interval of time to enable the oven to be cooled to a desired temperature. In order that the danger of explosion may be minimized and even entirely eliminated, the exhaust dampers 28 and 46 are controlled by a mechanism which is interlocked with the valve in the main gas line. To this end, control rod 57 is mounted upon the oven and connected to the dampers 28 and 46. The rod is provided with an operating handle 58 which has a fin 59 formed thereon. The fin is provided with a slot 60 which is adapted to receive a sector plate 61, mounted upon the spindle of a valve 62 in the main gas line 35. An operating handle 63 is provided on the spindle 62 and the sector plate 61 is formed with a boss 64

which is adapted to engage against the fin 59 and limit movement of the valve 62.

The foregoing mechanism, by providing the plurality of heat sources, results in an oven construction by means of which the heat within the oven chamber is efficiently and effectively controlled. This heat is uniform throughout all portions of the chamber and is effectively regulated by means of the dampers 47 and 48. Each 10 burner, together with its secondary air supply, is separately controlled and the temperatures upon the rotatable hearth as well as within the oven chamber may thus be effectively controlled. The baffles and ducts are so constructed that a 15 maximum heating and baking capacity is provided for a minimum size of oven, the safety and economy of which is far superior to existing constructions. There is no forced ventilation necessary and the oven chamber, as well as heating chambers and ducts are air-tight during operation. This tightness of the oven holds the heat and decreases the heat loss during the periods that the oven is shut down. Since the secondary air is supplied to all portions of each 20 burner uniformly, proper combustion is insured along the entire length of the burner.

It will be seen that the invention is not limited to the particular type of fuel utilized nor to the specific type of oven although to facilitate the description thereof, a rotary hearth type of oven has been shown.

While the invention has been described with specific reference to the accompanying drawings, it is not to be limited, save as defined in the appended claims.

We claim as our invention:

1. An oven, a plurality of independent heat sources therefor, an oven hearth in the oven, one of said heat sources applying direct heat below 40 the hearth and another of the heat sources being spaced from the oven, a flue from the second named source to the oven above the hearth, whereby the heat sources independently apply direct heat to the bottom and top of the hearth in independent heat paths, and means including the hearth to form a gas-tight baffle between the region above and below the hearth to maintain the heated gases from the independent heat sources in independent paths during the travel 50 thereof through the oven, whereby the condition of the heated gases discharged from the separate heat paths in the oven will indicate the condition of the heated gases in the independent paths in the oven.

2. An oven, a plurality of heat sources therefor, a movable oven hearth in the oven, means to direct heated gases from one of the heat sources over and in communication with the hearth, means to direct heated gases from another of the sources in an independent path beneath and in communication with the hearth and means including the hearth to form a gas-tight baffle between the region above and below the hearth.

3. An oven, a hearth in the oven, a crown over the hearth, means to direct heated gases between the hearth and crown and in direct communication therewith, separate means to direct heated gases beneath the hearth and in direct communication therewith, and means including the hearth to form a gas-tight baffle between the region above and below the hearth and to maintain the heated gases from the separate means in separate paths until discharged from the oven, whereby the condition of the heated

gases separately discharged from the oven will indicate the condition of the heated gases in the separate paths in the oven.

4. An oven, a movable hearth in the oven, a crown over the hearth forming with the hearth an upper heating chamber, said hearth forming with the oven a lower heating chamber, means to direct heat through the upper chamber, separate means to direct heat through the lower chamber, and means to maintain the heat so directed in separate paths including a heat trap between the hearth and oven.

5. An oven, a hearth in the oven, a crown over the hearth, means to direct heat between the hearth and crown, a flue having an opening adjacent the level of the hearth for receiving heated gases from between the hearth and crown, and separate means to direct heat beneath the hearth in a path independent of the path of heat between the hearth and crown.

6. An oven, a hearth in the oven, a crown over the hearth, a plurality of heat sources in the oven beneath the hearth, said hearth forming separate chambers above and below the hearth, means to direct heated gases from one of the sources direct through the entire chamber beneath the hearth, and means to direct heated gases directly in an independent path from other of the heat sources through the entire chamber above the hearth.

7. An oven, a rotatable hearth in the oven, a crown over the hearth forming a chamber thereabove, a chamber below the hearth, sealing means between the chambers above and below the hearth, separate heat sources, means to direct heat from one of the sources centrally of the hearth into the chamber thereabove, and means to direct heat from another of the sources independently of the first heat through the chamber beneath the hearth.

8. An oven, a rotatable hearth in the oven, a crown over the hearth forming a chamber thereabove, a chamber below the hearth, separate heat sources, means at the periphery of the hearth to seal the upper and lower chambers apart, an apron baffle on the hearth centrally thereof forming a duct to the upper chamber, a heat source communicating with the lower chamber, and a heat source and duct communicating with the apron baffle duct.

9. An oven, a hearth, a burner in the oven, a stack through which spent gases are discharged, a damper in the stack, a fuel supply having a control valve, and an interlocking mechanism between the valve and the damper to prevent opening the control valve when the damper is closed.

10. An oven, a hearth, a burner in the oven, a stack through which spent gases are discharged, a damper in the stack, a fuel supply having a control valve, separate manually actuated devices for actuating the valve and damper, and means to prevent the opening of the valve when the damper is closed.

11. An oven, a hearth, a burner in the oven, a stack through which spent gases are discharged, a damper in the stack, a fuel supply having a control valve, separate manually actuated devices for actuating the valve and damper, and means to prevent the closing of the damper when the valve is open.

12. An oven having a baking chamber, a plurality of heat sources therefor, means to direct heated gases from the sources in separate paths through the oven, and separate means to introduce cooling gases into the baking chamber.

13. An oven, a plurality of heat sources therefor, an oven hearth in the oven, means to direct heated gases from one of the heat sources over the hearth, means to direct heated gases from another of the sources in an independent path beneath the hearth, and separate means to introduce cooling gases into the respective paths one of said means introducing cooling gases directly into the baking chamber.
14. An oven, a rotatable hearth in the oven, a crown over the hearth forming a chamber thereabove, a chamber below the hearth, sealing means between the hearth and oven at the periphery of the hearth, a central duct passing through the lower chamber sealed therefrom and communicating with the upper chamber, separate heat sources, means to direct heat from one of the sources through the duct into the chamber thereabove, and means to direct heat from another of the sources independently of the first heat through the chamber beneath the hearth.
15. An oven, a plurality of independent heat sources therefor, a movable oven hearth in the
16. An oven having a baking chamber and a hearth therein, a bottom heat chamber beneath the hearth, a flue through which gases may be discharged from the bottom heat chamber, a plurality of burners in the bottom heat chamber, means to supply independent secondary air to each of the burners and means to vary the secondary air to the respective burners independently.
17. An oven, a plurality of heat sources applying direct heat below the hearth and another of the heat sources being spaced from the oven, a flue from the second named source to the oven above the hearth, whereby the heat sources independently apply direct heat to the bottom and top of the hearth in independent heat paths, and means including the hearth to form separate heat chambers and flue passes of the region above and below the hearth, whereby the application of direct heat to such regions may be effectively and independently controllable.
18. An oven having a baking chamber and a hearth therein, a bottom heat chamber beneath the hearth, a flue through which gases may be discharged from the bottom heat chamber, a plurality of burners in the bottom heat chamber, means to supply independent secondary air to each of the burners and means to vary the secondary air to the respective burners independently.

ROBERT H. STANIFORD.
